REFRIGERATOR CONSTRUCTION

William R. M. Very, Haddonfield, N. J., assignor,
by mesne assignments, to Servel, Inc., New
York, N. Y., a corporation of Delaware

Application February 10, 1930, Serial No. 427,104
Renewed July 13, 1939

15 Claims. (Cl. 62—116)

This invention relates to refrigerator construction and is particularly applicable to mechanical refrigerators, but may be used with ice. It has for its object the provision of a simple and cheap arrangement of the cooling element whereby the some forms part of the machine unit and may be mounted on the refrigerator cabinet therewith.

Another object is to provide for the quick freezing of ice.

Another object is to provide an arrangement whereby the ice drawers may be withdrawn from the cooling element or chamber without opening the door of the food chamber of the refrigerator cabinet.

Another object is to construct that part of the evaporator or cooling element projecting into the food chamber located within the refrigerator of metal only, and so that it need not contain refrigerant or brine.

A further object is to utilize the metal walls or other metal parts within the food chamber as parts of the evaporator and to conduct heat out of the food chamber and into the evaporator or cooling element.

Another object is to provide a refrigerator cabinet with cooling fins of a higher temperature than required for freezing ice, so that frosting and the resulting dehydration of the contents of the cabinet is reduced to a minimum.

Other objects will be apparent from the following description of one embodiment of the invention and the accompanying drawings showing the same, in which—

Figure 1 is a front view of a refrigerator cabinet and refrigerating machine mounted thereon, the door of the cabinet and machine casing being partly broken away to show the interior;

Figure 2 is a side view partly in section of the refrigerator and machine shown in Figure 1;

Figure 3 is a side view partly in section showing a modified form of the evaporator arrangement;

Figure 4 is a side view partly in section showing another modification of the evaporator arrangement.

The numeral 10 denotes a refrigerator cabinet of any suitable construction having within its heat insulated walls the usual food chamber or compartment 11. In order to cool this chamber it has heretofore been customary to place within the same ice, a coil of pipe, a cylinder or other element (commonly called a cooling coil or evaporator) containing brine or a refrigerant.

Such arrangements are open to several objections among which are the difficulty of connect-

ing these evaporators by means of pipes with the rest of the apparatus, the removal of water due to condensation or frosting, the danger of leaks of refrigerant or brine into the food chamber, etc. This invention eliminates these objections by providing a suitable evaporator such as the brine tank 12 mounted outside the food chamber. Projecting from this tank are a plurality of conductors 13, 14, 15, 16, 17, 18 preferably of metal, to which are secured in any suitable manner the metal plates 19, 20 which increase the area of the conducting surfaces within the chamber 11 in order to absorb heat therein.

The conductors may be solid or of tubular form. They may be of any suitable size. Their cross-section may be such as to maintain a food chamber of a given size at a given temperature and yet permit of a rapid freezing of water in the ice drawers 21, 22 which are not, as usual, placed within the food chamber 11 but are placed within the evaporator 12 and are therefore subject to the direct localized action of the refrigerant when a machine is used.

In a refrigerator adapted for ice, the ice would be placed in the evaporator or cooling element 12 and would operate as just described, but of course would not freeze water in the ice drawers. There are however, chemical mixtures already known, which if used in the evaporator or tank 12 will produce ice. The preferred arrangement however, is to provide a refrigerating machine which may be of any suitable absorption or compression type. For the sake of illustration a machine of the compression type will be generally described. As there are many suitable machines, the details of this will not be given except sufficiently to illustrate the invention described herein.

Within a frame having a chamber 23 of insulating material is placed the evaporator or tank 12. Within this tank in a recess 24 is placed a plurality of ice drawers 21, 22. Within the tank is a cooling coil 25 connected to the suction side of a compressor 26 of any suitable type. In this coil 25 the refrigerant gas is expanded after the same has been compressed in a compressor 26, cooled in the condenser 27 and passed through the usual expansion valve 28. An electric motor 29 drives the compressor. A casing 30 provided with suitable openings 31 on its sides encloses the compressor, condenser, motor and other usual and necessary controls, all these being mounted on the top of the frame carrying chamber 23, which frame forms a support or base for all of the aforesaid parts. The opening for the

ice drawers in 23 is closed by door 32, which, together with the casing 30, forms a cabinet or unit structure containing all the working parts adapted to operate and make ice if desired, and this unit structure may be placed upon the top of the refrigerator cabinet 10. Obviously this structure can be placed on the side of the cabinet, or elsewhere as long as the evaporator or cooling element projects into (or connects with heat conductors within) the food chamber.

The cabinet 10 has a portion of its external casing omitted at 7, 8 to allow the extended portion 9 of the brine tank 12 to rest on the insulation 33. A sufficient number of holes (or a single opening) may be made into the top of cabinet 10 to permit the downwardly projecting conductors 13, 14, 15, 16, 17, 18 to pass through the top wall 33 (or to contact with sockets therein as hereinafter described) thereof and enter the food chamber 11. These conductors may have the plates 19, 20 secured thereto before they are placed in position, or these plates may be detachable and be secured in position after the conductors are placed in said chamber.

The extended portion 9 of the brine tank may rest on the upper ends of the conductors 13, 14, 15, 16, 17, 18 and excellent contact obtained by pressure of gravity, or the conductors or portions of same may be made integral with the brine tank.

Within the chamber 11 is placed a shelf 34 for the drip pan 35. A baffle plate 36 is placed as shown in Figures 1 and 2 to cause air circulation to take place in the usual manner within the refrigerator. The food chamber has the usual door 37.

It will be observed from the foregoing that the complete machine is separate from the refrigerator cabinet and is easily placed thereon or removed therefrom without disconnecting any pipes to the evaporator which must be done when the evaporator is mounted within the food chamber, and that when in use, access can be obtained to the ice drawers by raising door 32 without the necessity of opening door 37 of the food chamber, and there are no refrigerant or brine pipes within the food chamber.

In Figures 3 and 4 are shown further modifications of the invention. Here, the machine unit is mounted separate from the evaporator and may be located away from the refrigerator cabinet, or in the base portion 38 thereof. The evaporator 12 is positioned below the bottom insulating wall 39 of food chamber 11. The conductors, one of which is shown at 40, Figure 3, pass upward from the evaporator 12 through wall 39 and into food chamber 11 where they extend upward to the top thereof and finally carry on their upper ends plates, one of which is shown at 41.

Access is obtained to the ice drawers 42 by providing a door 43 in the front of the cabinet 10. This may be opened independently of the food chamber door 44.

Figure 4 shows a modification wherein the conductors 45 are carried upward from the evaporator to the top of the food compartment within the wall 46 of the refrigerator cabinet. This is desirable in some cases in order to concentrate the cooling effect at the top of the food chamber and for other reasons.

In the arrangements shown in Figures 3 and 4, it is obvious that the conductors may be either permanently or detachably secured to the evaporator.

A further modification (not shown) would be to mount the complete high and low side unit on the side of the cabinet and have the conducting rods extend from the evaporator horizontally into the cabinet.

This would be particularly desirable in machines of the absorption type.

While the evaporator 12 is herein shown and described as a brine tank, it will be understood that it need not be of tank form, but the so called "direct expansion" system may be used, in which case the conductors projecting into the food chamber would be connected directly to the expansion coil or member 25. Such modifications are obvious and are all within the scope of the appended claims.

The inner metallic wall of the food chamber 11 may be used as a conductor. By connecting this wall to the conductors as shown in any of the figures (for illustration, wall 48 to conductor 45 via 45a) the wall or liner may be used to absorb heat. This utilization of the metallic surface may extend to the shelf 34 and drip pan 35, the usual metal shelves (not shown) or to other metal parts within the food chamber.

Slip sockets 49, 50 may be provided for the conductors shown in any of the figures so they may be easily removed from the food chamber for cleaning. Obviously these sockets can be mounted directly upon the evaporator 12 or at any other place, and may be between the conductors and the casing or liner, as shown at 51, Figure 2, where the upper conductor 18 fits into socket 51 which is secured to the inner metallic wall 48 of the food chamber. The lower half of the conductor 18a carries the plate 19, fits into the bottom of the socket 51, as shown.

These slip joints or sockets may be of any suitable form having the desired conductive and mechanical characteristics.

The usual controls such as a thermostat 53 for maintaining a predetermined temperature in chamber 11 and the motor overload protective device may be positioned as usual and as their construction, operation and location are well understood and bear no direct relation to the invention herein described, they are not herein described.

I claim—

1. In combination with a cabinet having a liner 50 enclosing a refrigerating chamber therein, a unit structure comprising a complete operating refrigerating machine including a cooling element, removable from said cabinet without disassembling said cooling element from the other parts of the unit structure, means for making ice in said cooling element and for removing said ice therefrom, and a heat conductor fixed to said cabinet in heat exchange relation to the refrigerating chamber therein and adapted to make thermal contact with the cooling element of said unit when same is combined with said cabinet.

2. In combination, a cabinet having walls forming a food chamber, a structure having walls forming a second chamber detachable from said cabinet, cooling means in said second chamber insulated from said first chamber, and a plurality of solid metallic conducting elements permanently secured to the wall of said cabinet in heat conductive relation to said food chamber and said cooling means.

3. In combination, a cabinet having walls forming a food chamber, a structure having walls forming a second chamber detachable from said cabinet, cooling means located entirely within

said second chamber, ice drawers in heat exchanging relation to said cooling means, and a plurality of metallic conducting elements independent of said cabinet walls in heat exchanging relation between said food chamber and said cooling means, said metallic conducting elements being permanently secured to said cabinet

4. In combination with a cabinet having within its upper portion a food chamber having insulated walls, a chamber below said food chamber, cooling means in said lower chamber, a solid conductor in heat exchanging relation between said chambers and mechanically connected to said cooling means, and a refrigerating machine within the lower portion of the cabinet connected to said cooling means and removable as a unit from said cabinet therewith.

5. In combination, a cabinet having a food chamber with insulated walls, a plurality of solid metallic conducting elements in said chamber having portions extending through at least one of said walls, and a refrigerating machine supported by said cabinet with a cooling element adapted to contact with said extended portions, said machine and said last cooling element forming a removable unit supported on said cabinet.

6. In combination, a cabinet comprising an insulated food chamber containing solid metallic conducting elements having extended portions in one wall thereof, a unit comprising a complete high and low side refrigerating system, said extended portions adapted to contact with said low side, and said unit adapted to be removed bodily without disturbing the interior of said cabinet or disconnecting piping connected therewith.

7. A refrigerator including a cabinet having a storage compartment to be cooled, thermal insulation enclosing said compartment, a unitary refrigeration apparatus including a cooling element providing a water freezing chamber adapted to receive ice cube forming trays or the like and having a contact surface, said apparatus unit being removably supported on the top of said cabinet, and thermal conducting means extending through said insulation and having a contact portion in thermal contact with the contact surface of said cooling element and having a portion within said compartment said thermal conducting means forming a path of flow for heat having a temperature gradient from the freezing temperature of said cooling element to a temperature above freezing in that portion of the heat conducting means within said compartment, whereby air in said compartment may be cooled without formation of frost and dehydration.

8. A refrigerator including a cabinet having a compartment to be cooled, thermal insulation enclosing said compartment, a unitary refrigeration apparatus including a cooling element providing a water freezing chamber adapted to receive ice cube forming trays or the like and having a contact surface, said apparatus unit being removably mounted on said cabinet outside of said compartment, and thermal conductive means extending through said insulation and having a portion in thermal contact with the contact surface of said cooling element and having a portion within said compartment for cooling the latter said thermal conducting means forming a path of flow for heat having a temperature gradient from the freezing temperature of said cooling element to a temperature above freezing in that portion of the heat conducting means within said compartment, whereby air in said compartment

ment may be cooled without formation of frost and dehydration.

9. In a refrigerator having a thermally insulated food storage compartment, refrigeration apparatus including a cooling element, said cooling element providing a water freezing chamber adapted to receive ice cube forming trays or the like, thermal insulation around said cooling element, and heat conducting means extending through said insulation and having a portion in thermal transfer relation with said cooling element and having another portion comprising a plurality of metal fins in contact with air in said food storage compartment for cooling the latter said heat conducting means forming a path of flow for heat having a temperature gradient from the freezing temperature of said cooling element to a temperature above freezing in said fins, whereby air in the food storage compartment is cooled without formation of frost or dehydration.

10. In combination with a cabinet having a cooling chamber therein, a unit structure comprising a complete operating refrigerating machine including a cooling element, heat insulation surrounding said element, and a casing about said structure having an opening therein to permit access to said cooling element, all said parts comprising said unit being removable from said cabinet without disconnecting said cooling element from the other parts, metallic cooling members within said chamber, and a metallic conductor adapted to make contact between said members and said cooling element when said unit is in place on the cabinet.

11. In combination with a refrigerating machine, a cabinet having a food chamber, cooling means outside said chamber, a metallic member constituting the cooling means in said chamber, and a metallic member adapted to form a separable connection between said first and second cooling means, said connection adapted to be made or broken without disconnecting said machine from said first cooling means.

12. In combination, a cabinet having a thermally insulated food storage compartment, a second thermally insulated compartment separable from said cabinet, cooling means located entirely within said separable compartment, and a heat conductor permanently located within said food storage compartment and passing through the walls of said compartments into contact with said cooling means.

13. In combination with a refrigerating machine, a cabinet having a food chamber, cooling means outside said chamber, a metallic member constituting a cooling means for said chamber, and a heat conductor adapted to form a separable connection between said first and second cooling means, said connection adapted to be made or broken without disconnecting said machine from said first cooling means.

14. A refrigerator including a first chamber wherein food is to be preserved, a second chamber wherein ice is to be made, a refrigerating unit including a cooling element in said second chamber, a metallic member in heat transmitting relation to said first chamber for transmitting cooling effect thereto and having an extended surface, a heat conductor in direct heat transmitting relation with said metallic member for transmitting cooling effect thereto, said heat conductor having removable connection with said cooling element whereby said cooling element transmits cooling effect to said heat conductor

when in functioning relationship, one or more ice forming members associated with said cooling element for production of ice, and insulation for retaining cooling effect in said respective chambers, said refrigerating unit including said cooling element constituting a removable unit, said metallic member and heat conductor being

arranged to remain in their structural and cooling effect transmission relationship to said first chamber upon removal of the refrigerating unit.

15. A refrigerator as set forth in claim 14 in which said metallic member is a liner bounding in part said first chamber.

WILLIAM R. M. VERY.
